UNITED STATES PATENT OFFICE.

KARL WIESER, OF RÜTTENSCHEID, NEAR ESSEN-ON-THE-RUHR, GERMANY,
ASSIGNOR TO FRIED. KRUPP, OF ESSEN-ON-THE-RUHR, GERMANY.

PROJECTILE.

SPECIFICATION forming part of Letters Patent No. 750,328, dated January 26, 1904.

Application filed January 9, 1902. Serial No. 89,043. (No model.)

To all whom it may concern:

Be it known that I, KARL WIESER, residing at Rüttenscheid, near Essen-on-the-Ruhr, Germany, have invented certain new and useful 5 Improvements in Projectiles, of which the following is a specification.

This invention relates to a projectile having a protecting-cap constructed of metal applied over the fuse, and has for its object to facilitate the application of the cap over the fuse screwed into the end of the projectile and permit a quick and sure separation of the cap from the fuse or projectile. These objects are attained according to this invention by having a cap consisting of a single piece of metal secured upon the outer face of the projectile and adapted to be removed from said fuse or projectile by splitting it from its base to its apex.

20 An embodiment of the invention is shown by way of illustration in the accompanying drawings, Figure 1 being a longitudinal section, and Fig. 2 a side view, of the embodiment.

25 The protecting-cap A is constructed of a thin sheet metal (aluminum or tin-plate being suitable) having a conical shape conforming to that of the fuse. Its height is such that it covers the separating-joint B between the projectile C and fuse D. In the form shown in Figs. 1 and 2 a wire E is riveted to a washer about half-way up on the inner face of the cap. This wire passes in a bow beneath the apex of the cap and onto a point in the rim of 35 the cap, which is diametrically opposite the

point of attachment to the cap, where it is bent outward around the edge of the cap and terminates in a loop F. A fastening for the cap, as well as the hermetic closure between the cap and projectile, may be accomplished in 40 different ways—for example, according to the form herein shown, by pressing a band H in the cap into an annular groove in the shell of the projectile or by covering the joint between cap and projectile with shellac. 45

Having described my invention, what I claim as new therein is—

An approximately conical-shaped metallic protecting-cap for projectile-fuses secured over the end of the fuse by fitting to the periphery thereof, and a tearing or ripping and detaching wire having one end secured to the cap on one side thereof, and passing thence to the other side of the fuse below the edge of the cap and causing the cap to come away with 55 the wire by splitting transversely, when the wire is pulled, the fitting part of the cap from the rim toward the apex, whereby one side of the cap is first opened and a pull is finally given near the apex to permit the cap to be 60 removed from the fuse through the slit thus formed.

In testimony whereof I have hereunto set my hand in the presence of two subscribing witnesses.

KARL WIESER.
